United States Patent

Des. 241,008
Patented Aug. 17, 1976

241,008

THREADED INSERT

Edward Di Loreto, Downey, Calif., assignor to Yale
Engineering Company, Downey, Calif.

Filed Aug. 18, 1975, Ser. No. 605,695

Term of patent 14 years

Int. Cl. D8—08

U.S. Cl. D8—272

FIG. 1

FIG. 2

FIG. 4

FIG. 5

FIG. 3

FIG. 1 is a perspective view of a threaded insert showing my new design, the opposite side being similar;

FIG. 2 is a front elevation thereof, the back side being similar;

FIG. 3 is a top view thereof, the bottom side being similar;

FIG. 4 is a left side view thereof as viewed in FIGS. 2 and 3;

FIG. 5 is a right side view thereof as viewed in FIGS. 2 and 3.

I claim:

The ornamental design for a threaded insert, as shown and described.
